In France December 9, 1938

4 Claims. (Cl. 2—169)

This invention relates to improvements in gloves and to a process of cutting and manufacturing same, and more particularly to new shapes resulting from new forms of cutting slits in the ball of the thumb-part of gloves.

It is an object of the invention to provide a thumb cut included in a pattern in which the finger parts of the glove run directly through to the crotch of the thumb in a strip-like part of the material which latter part is to be folded back in order to bring the top part of the thumb in the same direction as the other fingers.

Another object of this invention is to provide a thumb cut connected to a pattern in which the ball part of the thumb has a slit providing a tab which latter is to be folded back and joined to the palm part of the glove, thereby forming the crotch between thumb and index finger.

Still a further object of the invention is to provide a glove in which the ball part of the thumb has a slit providing a tab of the shape of a finger-part cut in one piece with its two fourchettes, the remaining body of the glove-pattern representing only the four back finger parts and three of the palm finger parts which latter are extended with allowance for the width of their fourchettes to be sewn to the back finger parts.

A still further object of this invention is to provide a thumb hole of any given shape (round, oval or similar) with a slit towards the finger parts for the insertion of the tab formed by a slit at the ball part of the thumb, which slit is adapted to the first mentioned slit of the thumb hole.

Yet another object of this invention is to provide a thumb hole with a slit ending at or between the finger parts of a glove in which the palm sides of the finger parts are not completely embodied; the thumb to be inserted is cut with allowance for making the completion.

Still another object of this invention is to provide a glove cut in two pieces only: One representing the back and palm of the hand, a thumb hole with a slit ending between the palm finger parts, three finger parts for the back and for the palm, the palm parts of which have extensions shaped like fourchettes to be sewn to the back finger parts, and the back part of another finger; the other piece representing the palm finger part of the last mentioned finger with an extension shaped like its two fourchettes to be sewn to the back part of this finger, the palm finger part running directly through to the crotch of the thumb in a strip-like part of the material which is cut in one piece with the thumb to be inserted, and

which is adapted to the shape of the slit of the thumb-hole.

Gloves made in accordance with this invention become stronger and wear better, as the invention results in the suppression of seams, particularly in the crotch between the index finger and the thumb.

Gloves, and particularly gloves made of fabric, leather or other material, were hitherto cut to one or different pattern, alone or together representing the back and the palm of the hand with tongue-shaped finger parts, the thumb hole, the thumb and the fourchettes. Generally thumb and fourchettes were cut separately, inserted and sewn later on. This separate cutting involves double work in marking and in matching glove, thumb and fourchettes before sewing. Moreover all shapes of thumbs hitherto known require seams with or without gusset across the crotch between thumb and index in order to give the width for the free movement of the hand and the thumb. One very common shape has a slit in the top part of the thumb between the two joints where a tab is inserted and sewn. Such a seam between the joints of the thumb even appears where, hitherto, attempts have been made to cut glove and thumb in one piece. None of the hitherto known shapes at the same time allowed avoiding any cross-seam in the crotch between the joints of the thumb and the index finger, any gusset to be inserted, and insuring a perfect fit, sufficient width in the crotch, hard wear and free movement of the thumb.

I attain these objects in both utilizing new patterns for the thumb with a slit of any desired shape only in the part covering the thenar eminence or ball, and new shapes of the opening for the insertion of the thumb of the glove.

According to this invention glove body and thumb are cut in one piece so that one side edge of the glove, beginning at the finger parts, continues as a slit separating the ball part of the thumb from the body of the glove and is then intersected by a strip-like piece representing the seamless crotch between thumb and index, and joining the thumb to the body of the glove, forms therefrom a part of the opening for the insertion of the thumb, and terminates in any desired shape. The top of the thumb is directed just opposite to the direction of the top of the other tongue-shaped finger parts. To give the thumb its natural position the strip-like connexion of thumb and glove-body, when being sewn, will be folded back along a line between the end of the 55 side edge of the glove pattern at the ball of the

thumb and the continuation point of this edge, when it forms the thumb opening.

This idea can be executed in various ways, as the beginning of the side edges of the glove to be joined by a seam can be located at any place between or on the finger parts of the hand. The second edge, to be sewn to the edge with thumb, is adapted to the geometrical shape of the first edge from its beginning to the end of the slit separating ball and glove, but projected in form of an angle or curve with allowance for the width necessary for the free movement of the thumb. The thumb is inserted between the two side-edges. It can take any fancy shape and extension.

It is, of course, possible to leave only the inside part of the thumb attached to the body of the glove and to join the other part in the same or different material by seams and in any desired shape or fancy form.

According to this invention, glove body and thumb may be cut in one piece so that the back of the glove runs seamless into the ball, one side edge of the glove, beginning at the finger parts, continues as a slit separating the top part of the thumb from the body of the glove, follows the shape of the thumb and ends in any desired shape. The novelty is the shape of the thumb, which is, at its free ball part, provided with a slit leaving a tab. The second edge to be sewn to the edge with thumb, is adapted to the geometrical shape of the first edge from its beginning to the end of the slit separating thumb and glove, but deviated with allowance for the width necessary for the free movement of the thumb, and continues then with a cut-out for insertion of the free ball part of the thumb. The tab, left at the latter by the slit, is folded back along a line between the end of the slit and the outer endpoint of the thumb curve, and inserted between the edges. They join towards the wrist in any desired shape. It is important that the tab inserted between the edges is located entirely in the palm of the hand and no cross-seam is to be found at the thumb.

According to the invention the beforementioned tab of the thumb may be extended with allowance for the tongue-shaped palm finger part of the ring finger having the additional width of the two fourchettes on both of its side edges. The cut-out for insertion of the free ball part of the thumb is adapted to the shape of the slit at the ball part of the thumb. The tongue shaped palm part of the ring finger not being provided in the pattern of the body of the hand, sufficient material is available to extend the palm parts of the little finger and of the middle finger with allowance for the width of one fourchette each, and on the free side edges of the glove, the index and the middle finger are cut with allowance for the width of one fourchette each. This glove has all the seams at the back finger parts of the hand and no seams at the finger parts of the palm, with the exception of the thumb. All parts of this glove are cut in one piece. When folding back the tab of the thumb, the first part is inserted between the edges of the glove, the extension forms a strip-like connexion between the crotch of the thumb and the end of the extended tab, which is inserted between the palm parts of the little and middle finger forming the palm part of the ring finger. In the crotches between the palm parts of the index, middle finger, ring finger and little finger, slits are provided which allow to form the fingers of the glove in sewing the edges of the palm finger parts to the edges of the back finger parts.

sewing the edges of the palm finger parts to the edges of the back finger parts.

No cross seam at the crotch of the thumb will also be obtained according to this invention, if a thumb with a slit in its ball part is cut separately and inserted and sewn into a special thumb-hole provided in the body of the glove. Preferably a pattern is employed having a thumb-hole of any shape e. g. round or oval, ending in a slit of any geometrical shape, e. g. straight or curved, which takes any direction towards the crotch of the palm finger parts. To this slit, another slit is adapted in the large ball part of the thumb which leaves a tab to be folded back and is to be inserted and sewn in between the slit of the thumb hole, in which the thumb will be sewn. The thumb can have any fancy shape. It is possible to utilize only the interior half-section of the thumb and to add the other half-section separately.

According to the invention the thumb-hole may be provided with a slit, which forks in the palm of the hand and extends up to the crotch of the palm finger parts or along these parts. This forked slit will cut off parts of the palm finger parts of the glove pattern. But the tab of the thumb will be extended with exact allowance for these parts, so that they are cut in one piece with the thumb and inserted in between the forked slit of the thumb hole and sewn to the body of the glove.

This allows finally to make a glove of two pieces only without any fourchettes or gusset. In this case the side edges of the glove begin in the crotch between the palm parts of the ring finger and the little finger in any desired shape; the slit of the thumb-hole forks, one branch ending in the crotch between the index and middle finger, the other between middle finger and ring finger of the palm; the tongue-shaped palm part of the middle finger is not provided in the pattern of the body of the hand, but the tab of the thumb is extended with allowance for this finger part and the additional width of the two fourchettes on both of its side edges. The middle finger part of the palm not being provided in the body of the glove pattern, sufficient material is available to extend the palm side of the index finger and of the ring finger with allowance for the width of one fourchette each. This glove will have all the seams at the finger parts of the back of the hand and no seam at the finger parts of the palm, with the exception of the thumb. When inserting the thumb into the hole, the tab is folded back and inserted between the edges of the forked slit of the thumb-hole, being thus a strip-like connexion between the crotch of the thumb and the end of the extended tab, which is inserted between the palm parts of the index and ring finger, forming the palm part of the middle finger. In the crotches between the palm parts of the index, middle finger, ring finger and little finger, slits are provided which allow to form the fingers of the glove in sewing the edges of the palm finger parts to the edges of the back finger parts.

Embodiments of the invention are illustrated in the accompanying drawing, in which

Fig. 1 shows the pattern of a thumb cut in one piece with the body of the glove and having an edge at both sides of the ball part which are inserted in the openings provided at the side edges of the glove body. The finished palm side of the glove is shown in Fig. 2.

Fig. 3 shows the pattern of a glove with thumb-

having an edge at one side of the ball to be sewn at the palm of the hand only, as illustrated in Fig. 4.

Fig. 5 is the pattern of an all in one glove without fourchettes. Fig. 6 is the view of the palm of the finished glove.

Fig. 7 is the pattern of the common thumb to be inserted.

Fig. 8 is the pattern of a left hand thumb with slit at its ball, to be inserted in the thumb-hole illustrated in the glove pattern Fig. 9.

Fig. 10a represents the glove body, Fig. 10b the thumb with one finger part to be inserted in said glove body of Fig. 10a. The view of the palm of the thus assembled glove is shown in Fig. 11.

Similar numerals refer to similar parts throughout the several views.

1 is the tip of the thumb, 2 the end of the slit at the ball near the crotch, 2' the edge of the glove to be joined to this slit, 3 the edge of the palm part of the thumb near the crotch, 3' the edge of the back part of the thumb near the crotch, 4 and 4' the thumb opening.

When sewing the glove the pattern is folded round the index, the little finger and the thumb, so that 2 and 2', 3 and 3' are sewn together.

Fig. 1 is the illustration of the first part of the invention. Between 2 and 3 runs the strip-like connexion of index and thumb, which forms the crotch. In this example the thumb has an extension of the ball towards the wrist. The projected part 2' of the thumb-free edge of the glove pattern is to be inserted between the two edges of the slit 2. Fig. 2 shows this slit, which, after folding the thumb around the axis 2-3 and bringing the top 1 of the thumb in the direction of the other fingers, becomes a part of the seam in the palm of the hand.

Fig. 3 illustrates a second embodiment of the invention. The tab 2-5-3 is folded round the axis 2-3 and inserted between the points 2', 3', 5' and 5'' of the side edges of the glove body, the point 5 of the tab is sewn between 5' and 5'', thus forming the crotch of the thumb, as shown in Fig. 4.

Fig. 5 is the pattern of a glove cut all in one piece. The tab 6-5-2-3 of the thumb is folded round 2-3 and inserted between the point 2', 3', 5' and 5'' of the side edges of the glove; point 5 of the tab is sewn to 5', the strip-like extended tab 6 then turns towards the points 8' and 7', so that part 6 forms the finger part of the ring finger. The slits 8' and 7' allow to fold a part of the middle finger and of the little finger so that the edges can be sewn like fourchettes to the back finger parts. Points 7 and 7', 8 and 8' come together. The slits 7 and 8 of the part 6 allow to sew its edges like fourchettes to the back finger part. So do the slits at the outer edges of the index and middle fingers. It is to be seen in Fig. 6 that the part between 5 and 7 is superposed to the part of the glove body between 5' and 7'.

When a tab is to be sewn to 9' of the common thumb of Fig. 7, a seam between the joints of the thumb will always be apparent. In the top part of my thumb Fig. 8, the edges 1-3 and 1-3' are sewn together, the tab 5 is folded round the axis 2-3 and inserted in the palm of the hand between the edges of the slit 2'-13 of the thumb hole in Fig. 9. The tab 5-3-2 remains entirely in the palm of the hand.

Fig. 11 refers to another embodiment of the invention. In Fig. 10a the slit of the thumb hole forks, the branches going from 2' to 10' and 11'. In Fig. 10b the tab of the thumb is extended with allowance for the part 12, is to be folded round the axis 2-3 and to be inserted between the edges 2'-10' and 2'-11', so that part 12 forms the finger-part of the middle finger as illustrated in Fig. 11. The slits 10' and 11' allow to fold a part of the index and of the ring finger so that their edges can be sewn like fourchettes to the back finger parts. Points 10 and 10', 11 and 11' come together. The slits 10 and 11 of part 12 allow to sew its edges like fourchettes to the back finger-part. So do the slits at the outer edges of the ring finger and the little finger.

It can thus be recognized that according to this invention there has been provided in the new glove a single piece of material forming a finger part, thumb, and a strip-like member, said thumb being separated from said finger part except by said strip-like member connecting the base of the thumb to the base of the finger part, said thumb being disposed with its tip extending in opposed relation to the tip of said finger part, said strip-like member forming a seamless crotch between said thumb and said finger part in assembled condition of said glove.

Having thus described the invention what is claimed as new and desired to be secured by Letters Patent is:

1. In a glove, a single piece of material forming a finger part, thumb, and a strip-like member; said thumb being separated from said finger part except by said strip-like member connecting the base of the thumb to the base of the finger part, said thumb being disposed with its tip extending in opposed relation to the tip of said finger part, said strip-like member forming a seamless crotch between said thumb and said finger part in assembled condition of said glove.

2. In a glove, a single piece of material forming palm, back, thumb, at least a finger part of said glove, and a strip-like member; said thumb being separated by said finger part except by said strip-like member connecting the base of said thumb to the base of said finger part, said strip-like member forming a seamless crotch between said thumb and said finger part in assembled condition of said glove.

3. In a glove, a single piece of material forming palm, back, thumb, at least the index finger of said glove, and a strip-like member; said thumb being separated from said index finger except by said strip-like member connecting the base of said thumb to the base of said index finger, said strip-like member forming a seamless crotch between said thumb and said index finger in assembled condition of said glove.

4. In a glove, a single piece of material forming palm, back, thumb, at least a finger part of said glove, and a strip-like member; said finger part being the third finger of said glove, said thumb being separated from said finger part except by said strip-like member connecting the base of said thumb to the base of said finger part, said strip-like member forming a seamless crotch between said thumb and said finger part in assembled condition of said glove.

HILDE DAVIDSOHN,
